TRANSFORMER

Charles H. Dunton, Berkeley, Calif.

Application March 14, 1944, Serial No. 526,403

4 Claims. (Cl. 175—356)

This invention, a transformer, is a new and unconventional type of transformer in which the secondary coil is shielded from the primary coil and core by a conductive sleeve. Its construction is opposite to that of the conventional series transformer in that the secondary coil takes the place of the laminated core to form the axial member, while the laminated core takes the place of the conventional primary and secondary, having its laminations encircling the cluster of secondary turns, and with the primary alone wound around the core from end to end with the stands of the primary winding parallel to those of the secondary winding. In addition, the entire secondary winding is shielded by a continuous series of preferably high-conductivity rings which are parallel to the core laminations and with their axes coincident with the axis of the secondary.

The objects and advantages of the invention are as follows:

First, to provide a transformer of a new and unusual type of construction.

Second, to provide a transformer which is highly efficient and which eliminates flux leakage across the ends of the coils.

Third, to provide a transformer in which the secondary structurally replaces the conventional laminated core with the laminated core instead encircling the secondary transverse to the lay of the secondary wires and with the primary winding parallel to that of the secondary.

Fourth, to provide a transformer as outlined with a shield of highly-conductive rings encircling the secondary throughout its circular extent, and with the shield formed of interlocking rings insulated from each other and located between the primary winding with its laminated core, and the secondary winding.

Fifth, to provide a transformer in which the secondary winding is completely enclosed by a shield formed of interlocking rings encircling the secondary and insulated from each other, and with the laminated core diametrically encircling the shield and having the primary wound axially thereabout with the primary windings parallel to those of the secondary, with the shield functioning as a stop against leakage lines of force and as a neutralizer of counter E. M. F. set up by the secondary.

Other objects and advantages of the invention will become apparent as the following description is read on the drawing forming a part of this specification, and in which:

Fig. 1 is a plan view of the invention.

Fig. 2 is a longitudinal section through one of 55

the primary units along with the associated portions of the secondary and shield.

Fig. 3 is a section taken on line 3—3 of Fig. 2.

Fig. 4 diagrammatically illustrates the invention.

The invention consists of a secondary coil 10 of comparatively great circular length equivalent to the circular length of the core of a series transformer, and having terminals 11 and 12. This 10 secondary coil structurally takes the place of the laminated core of the conventional type of series transformer. The number of turns and size of wire are calculated on the same basis as for other types of transformers, which likewise applies to 15 the primary, and to the area of the magnetic core. This secondary may be prewound if the other parts are made assembleable thereabout as will hereinafter be explained.

The sleeve 13 is provided for the purpose of 20 centering the secondary, and is made of insulating material, preferably in halves to assemble about the prewound secondary, and has spacer members 14 formed exteriorly to center the secondary in the shield and to provide a passage 25 for fluid. However, if no fluid circulation for cooling is required, this sleeve may be dispensed with.

Encircling the secondary throughout its circular extent is a shield which consists of rings 15 which 30 should have relatively low cross-sectional resistance and therefore preferably formed of highly conductive metal such as annealed copper or aluminum, though other metals and alloys can be substituted so long as the cross-sectional resistance is kept below one milohm. These rings are 35 preferably formed in halves with the faces made to interlock, such as by the tongue-and-groove arrangement as indicated at 16. These rings can be assembled around the secondary and sleeve and will interlock if the joints of the respective rings are broken, preferably about at right angles to each other, with the joints of one pair of halves located at 17 and those of the adjoining pair at 18. The halves are not insulated at the ends, 40 but the respective complete rings are insulated on their contacting faces at 19, such as by mica, or by applying a thin film of Bakelite or similar insulating varnish to these faces—very little insulation being required because of the extremely 45 low voltage set up in the rings.

The connecting portions 20 of the shield can be made in the form of upper and lower halves of a quarter torus, suitably bolted or riveted together as indicated at 21, or these portions may be formed of a series of tapered rings as indicated

at 22. Thus the secondary is completely shielded throughout its circular extent.

The primary core consists of laminations 23 which like the shield may consist of half rings with the joints staggered at assembly, to permit 5 their assembly within, after the primary coils have been wound, to form a complete magnetic circuit about a portion of the secondary coil and shield.

The primary coil 24 is illustrated as consisting 10 of only a single layer of a few turns over one portion of the core, which limitation in the drawing was made for clarity, though any number of turns or layers may be used, and the coil may be wound throughout the circular extent of the core, 15 or a series of coils 24'-24'' as illustrated in Figs. 2, 3 and 4 may be used, separate coils as shown facilitating the assembly of primary winding and core.

The primary coils in Fig. 1 are shown connected in series as indicated by the connections 20 25, though the transformer is not limited to series connections either between the respective primary units, or between respective coils in a primary unit or on each core, either or both of which 25 can be connected in series, series-parallel, or parallel, in accordance with the governing factors and the results to be achieved. The terminals of the primary circuit are shown at 26 and 27.

In the diagram, Fig. 4, the secondary 10 is 30 shown complete, with one half shield ring the diametric ends of which are 15' and 15'', and one primary unit with two primary coils and opposite sections of the core indicated as 23' and 23''.

The arrows indicate the flow of current, E. M. F., and flux in and between the respective elements, with the flux diametrically threading the secondary from the shield, and the E. M. F. set up by the secondary opposed diametrically in the shield. The shield is excited only through the 40 flux from the secondary with consequent complete neutralization of the individual shield rings, with the flux in the adjacent faces of adjacent shield rings opposed and thereby neutralized.

In the event that cooling of the secondary and shield is found desirable, gravity circulation of fluid is secured simply by supporting the transformer at one corner at 28 and in an upright position, and providing an intake 28 and an outlet 29. Or in the position shown, force feed cooling may be employed, by attaching the source of fluid under pressure to one passage 28. The fluid will have equal resistance in both directions, passing through the clearances 30 formed by the projections 14 on the outside of the sleeves 13, escaping through the diametric passage 29. Obviously other methods of cooling may be substituted, the simplest method having been illustrated.

It will be understood that variations in construction and arrangement of parts, which variations are consistent with the appended claims, may be resorted to without detracting from the spirit or scope of the invention, or sacrificing any of the advantages thereof.

I claim:

1. A transformer, in combination, a magnetizable ring core having a primary wound about a portion thereof with the turns parallel to the axis of the ring, and toroidal secondary winding comprising a plurality of turns and axially threaded through said ring core and extending about one side thereof with the turns parallel to those of the primary winding; a conductive non-magnetic metal shield completely enclosing said secondary winding and passing, with the secondary therein, through said ring core, and formed of rings of relatively small cross-section with interlocking faces insulated from each other.

2. A transformer comprising; a secondary winding of non-magnetic insulated metal wire, a magnetic core, and a primary winding formed about one side of said core with the lay of the wires parallel to those of the secondary winding, and a shield between the secondary winding and the core with its primary winding and consisting of non-magnetic facially interlocking conductive rings insulated one from the other, with each ring formed in segments to facilitate assembly, and with the ends of the segments of adjoining rings angularly stepped for interlocking by co-operating segments to form complete rings, said shield being formed throughout the circular extent of the secondary winding to completely shield the same.

3. A transformer comprising; a secondary coil consisting of a plurality of turns of insulated wire and of relatively large internal diameter; a laminated ring core encircling one side of said secondary winding, and a primary winding encircling one side of said ring core with the lay of the wires in primary and secondary parallel to each other; a shield encircling said secondary winding throughout its circular extent and passing through said ring core to shield the secondary winding against primary flux, and consisting of non-magnetic conductive rings having facially co-operative locking means and with the faces insulated.

4. A transformer comprising; a secondary winding of relatively great circular extent; a plurality of primary units encircling equi-angularly spaced portions of said secondary winding and each consisting of a magnetizable ring core and a plurality of turns, and with the turns parallel to those of the secondary, with the primary windings electrically connected and having terminals, and terminals for the secondary winding; a conductive shield completely encircling said secondary winding throughout its circular extent and consisting of a continuous series of non-magnetic rings insulated from each other and having co-operative interlocking means to align the peripheries of the rings, and each ring being formed in segments to facilitate assembly.

CHARLES H. DUNTON.
